(57) CLAIM

The ornamental design for a small oval baking pan, as shown.

DESCRIPTION

FIG. 1 is a perspective view of the inventive design for a small oval baking pan;

FIG. 2 is a side elevational view of one side of the FIG. 1 design;

FIG. 3 is a side elevational view of the opposite side of the FIG. 1 design; the opposite side being a mirror image of the one side;

FIG. 4 is a top plan view of the FIG. 1 design;

FIG. 5 is a bottom plan view of the FIG. 1 design;

FIG. 6 is a front end elevational view of the FIG. 1 design;

FIG. 7 is a back end elevational view of the FIG. 1 design;

FIG. 8 is a vertical sectional view taken along the line VIII—VIII of the FIG. 4 design; and,

FIG. 9 is a fragmentary perspective view of the bottom of the FIG. 1 design.
